UNITED STATES PATENT OFFICE

LEE M. BEALL, OF TULSA, OKLAHOMA

FURNACE WALL

Application filed March 27, 1929. Serial No. 350,212.

My invention relates to furnace wall construction and more particularly to a double furnace wall including spaced wall portions and bonding blocks for interlocking the wall portions in spaced relation.

The principal object of the present invention is to permit contraction and expansion of the interlocked wall portions relative to each other.

10 A further object of the invention is to provide for circulation of air through the interlocking layers between the sections of a wall.

In accomplishing these and other objects of the invention, I have provided improved 15 details of structure, the preferred forms of which are illustrated in the accompanying drawings, wherein:

Fig. 1 is a perspective view of the outside 20 of a double furnace wall partly broken away for better illustration of the bonding blocks connecting the wall portions.

Fig. 2 is a detail perspective view of a bonding block.

Fig. 3 is a detail perspective view of a filler 25 block for use with the bonding blocks.

Referring in detail to the drawings:

1 designates a double furnace wall including an inner wall 2 for enclosing burners, 30 boilers and the like and subject to expansion and contraction due to the heat of the burner, and spaced from an outer enclosing wall 3 to form an air space or passage 4 between the walls so that air passing to the burner is conducted through the air space and tends to cool the inner wall.

The inner wall 2 comprises a plurality of horizontal sections 5 composed of layers of standard fire brick 6 laid lengthwise with thickness of the wall, the sections being separated by horizontal bonding layers or sections 7 composed of my improved bonding blocks 8 and filler blocks 9 presently described.

45 The bonding block 7 includes a substantially rectangular shaped body 10 of greater length than the standard brick 6, and having flat top and bottom surfaces 11 and 12 and flat side faces 13 and 14 tapered longitudinally and inwardly from the end 15 to a point 16 adjacent the end face 17 and forming a wedge-

like portion 18 and tapered outwardly from the point 16 to form lateral interlocking jaws 19 on a head portion 20. The wedge portion 18 is equal in length to the standard brick 6 and the blocks are adapted to be laid on the brick 55 sections in horizontally spaced relation for receiving the filler blocks 9, and with the ends 15 in flush alignment with the inner face of the wall so that the interlocking jaws of the head portion protrude from the wall for 60 engagement with bonding blocks in the outer wall as hereafter described.

A groove 21 is located centrally between the jaws 19 and extends vertically across the end face 17 to provide an air passage 65 between the blocks of the respective wall portions when assembled.

The filler block 9 comprises a wedge shaped body 22 equal in thickness to the bonding block 7 and equal in length to the standard 70 brick 6.

The filler block is provided with flat end surfaces 23 and 24 for alignment with surfaces of the wall, and with tapered side faces 25 conforming to the tapered side faces 13 75 and 14 of the bonding blocks, whereby the filler block is adapted to fit snugly between bonding blocks for binding the blocks in the wall structure.

Formed in the top side 26 of the filler block 80 and adjacent the end 23 are a recess 27 and a connecting groove 28 for receiving the head and shank portions of a bolt 29 when the block is used in the outer wall 3 presently described.

The outer enclosing wall 3 is composed of a plurality of horizontal sections 30, each consisting of layers of standard fire brick laid lengthwise with the length of the wall and capped by a layer of the bonding blocks 7 and 90 filler blocks 9.

The sections 30 correspond in height to the sections 5 of the inner wall and the bonding blocks 7 are offset horizontally so that the head portions of the blocks in the inner wall 95 and the tapered jaws 19 serve to restrain the members from sideward shifting, and to permit vertical shifting movement between the members caused by contraction and expansion 100 of the wall.

A steel frame work is constructed outside of the outer wall for reinforcing purposes and consists of vertical I-beams or buck stays 31 in abutment with the surface of the wall and connected by horizontal paired angle bars 32.

5 The bars 32 are positioned in parallel alignment with the bonding layers and spaced apart for receiving the bolts 29 connected with the filler blocks. Washers 33 and nuts 10 34 are applied on the bolts for securing the filler blocks against displacement from the outer wall.

When the wall is completely assembled as heretofore described, the outer wall is reinforced and retained by the steel frame work 15 and the bonding blocks 9 serve to provide an interlocking connection between the outer wall and the inner wall, whereby the inner wall is also reinforced against horizontal side 20 strains caused by contraction and expansion due to its subjection to the heat of combustion.

It is to be particularly noted that while the bonding blocks interlock and prevent sideward shifting or tilting of the wall portions, the vertical sliding fit between the head 25 portions 20 of the blocks permits the inner wall 2 to expand and contract vertically with relation to the wall portion 3 and its brick layers and sections may move relatively to 30 the substantially unmoved outer wall and without affecting the horizontal bond between the wall portions.

What I claim and desire to secure by Letters Patent is:

35 1. In a furnace wall of the character described including spaced walls formed of horizontal sections, wall-connecting means including a series of tapering locking blocks spacing the sections of each wall, tapering 40 filler blocks spacing the locking blocks in each series, the locking blocks in each wall having diverging jaws projecting toward the opposite wall adapted for interlocking engagement with the jaws of locking blocks in 45 said opposite wall to form a partition across the spacing between said walls, and being provided with apertures for passage of air through the partition.

50 2. In a furnace wall of the character described, horizontally spaced walls each comprising a plurality of horizontal sections and a connecting element spacing the sections, said connecting element including a pair of bonding blocks in each wall having projecting 55 portions adapted to receive the projecting portion of a bonding block in the opposite wall, a filler block interlockingly engaging each pair of bonding blocks and spacing the same, and having a socket, and means including a retainer adapted to seat in said 60 socket of a selected filler block for securing the connecting element to the furnace wall.

65 3. In combination with spaced furnace walls comprising horizontal sections, and a vertical support, interlocking means inter-

posed between the sections of the walls for connecting the same including a member having a socket, a plate connected with the support, and a retainer engageable with the plate and having a head seatable in said socket for 70 securing the walls to the support.

4. In a structure of the character described including a vertical support and a wall including horizontal sections, wall-retaining means including a series of tapering blocks 75 spacing said sections, tapering filler blocks spacing the locking blocks and anchored thereby, a selected filler block being provided with a socket, and a retainer engageable in said socket and connected with the support. 80

5. In a furnace wall of the character described including spaced independently supported walls formed of horizontal sections, wall-connecting means including a series of tapering locking blocks spacing the sections 85 of each wall, and tapering filler blocks spacing the locking blocks in each series, the locking blocks in each wall having portions projecting toward the opposite wall for interlocking engagement with similar portions of 90 locking blocks in the opposite wall.

6. In a furnace wall of the character described, spaced outer and inner walls including horizontal sections, and a series of wedge-shaped alternately oppositely directed blocks 95 spacing the sections of each wall, selected blocks in each series having portions projecting across the space between the walls and engaged with similarly projecting portions of blocks in an opposite wall to form a horizontal partition, said projecting portions being provided with apertures for passage of air 100 through the partition.

In testimony whereof I affix my signature.
LEE M. BEALL.
